(57) **CLAIM**

The ornamental design for a diagnostic reader device, as shown and described.

DESCRIPTION

FIG. 1 is a top, front, and right side perspective view of a first embodiment of a diagnostic reader device;

FIG. 2 is a bottom, rear, and left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof, the right side being a mirror image;

FIG. 8 is a top, front, and right side perspective view of a second embodiment of a diagnostic reader device;

FIG. 9 is a bottom, rear, and left side perspective view thereof;

FIG. 10 is a front elevation view thereof;

FIG. 11 is a rear elevation view thereof;

FIG. 12 is a top plan view thereof;

FIG. 13 is a bottom plan view thereof; and,

FIG. 14 is a left side elevation view thereof, the right side being a mirror image.

The broken lines depict portions of the diagnostic reader device that form no part of the claimed design; the broken lines form no part of the claimed design.
